FOOTWEAR

Julius Farina, Springfield, Mass.

Application June 20, 1938, Serial No. 214,791

4 Claims. (Cl. 36—42)

My invention relates to improvements in footwear and more particularly to devices for securing the heels to soles of shoes and the like.

One of the principal objects of my invention is to provide a device for securing the heel to the sole of a shoe which is so fashioned and constructed as to permit adjustment of the heel relative to the sole before finally securing the heel to the sole.

10 Another object of my invention is to provide a device of the above described character which is simple in construction, reliable in use, efficient in operation and economical in manufacture.

Other objects and advantages will be apparent 15 from the following description, appended claims and annexed drawing.

Referring to the drawing wherein like reference characters designate like parts throughout the several views:

20 Figure 1 is a side elevation of a heel portion of a shoe, partly in section, illustrating my device securing the heel to the sole of the shoe.

Figure 2 is a fragmentary top plan view of a heel portion of the shoe, the insole lining being broken away to illustrate my invention applied thereto.

Figure 3 is a sectional view taken on the line 3—3 of Figure 1.

In practicing my invention I provide a shoe, 30 the heel portion of which is illustrated as comprising outsole, insole and insole lining 5, 6 and 7 respectively and a heel 8 attached to the outer face of the outsole.

The outsole and insole are fashioned with an 35 aperture 9, the upper section of which is of a larger diameter than the lower section. Secured within the upper section is an inverted cap 10 formed with an interiorly disposed concave seat 11 having a bolt opening 12 extending therethrough. The upper end of the cap 10 is fashioned with a circumferentially extending flange counter-sunk within the insole 6.

The upper face of the heel 8 is of a like contour as the lower face of the outsole 6 and is initially attached thereto by means of glue, cement or the like whereby to secure the upper face of the heel in appressed condition with the lower face of the outsole 5. The heel is fashioned with a vertically extending socket 13 in the upper section thereof and with a horizontally extending slot 14 effecting communication with the exterior of the heel through the front or forward face thereof. A threaded bolt 15, of a diameter less than the diameter of the socket 13, is positioned 50 within the socket 13 and is provided with a hemi-

spherical shaped head 16 located within the cap and in engagement with the seat 11 thereof.

Said bolt 15 is provided with a downwardly extending shank 17 having a pointed end 18 adapted to penetrate the heel below the lower end of the socket 13. The shank 17, adjacent the head 16, is of a reduced diameter to permit swiveling movement of the bolt relative to the cap 10 whereby to effect adjustment of the bolt relative to the heel. Secured within the slot 14 by the threaded engagement of the bolt passing therethrough is a nut 19 and interposed between the nut 19 and the upper wall of the slot 14 is a spring washer 20 for maintaining the nut 19 locked to the bolt 15. The nut, together with the washer 20, is inserted within the slot 14 from the front face of the heel after the heel has been adjusted to the outsole 5. When the heel has been applied to the outsole 5, the cap 10 having the bolt 15 extending therefrom is 20 inserted within the aperture 9 and the bolt threaded into the nut 19 to bind the heel to the outsole against dislodgement therefrom.

From the foregoing it will be noted that the heel is capable of being applied and adjusted 25 on the outsole previous to the insertion of the nut and introduction of the bolt, thereby permitting the same nut and bolt to be used with each heel replacement. When the parts are thus assembled, the insole lining is applied over the 30 outer face of the insole and conceals the head of the bolt and cap from view.

What I claim is:

1. In a shoe, the combination of a sole provided in the heel attaching section with an aperture 35 extending therethrough, a cap within said aperture, a heel appressed against said section and formed in the upper section thereof with an upwardly extending socket and a slot intersecting said socket and effecting communication with the exterior of said heel, a nut positioned in said slot and capable of being inserted in and removed therefrom when said heel is against said sole, and a bolt swiveled to said cap and extending through said nut for fixing said heel to said 40 sole.

2. In a shoe, the combination of a sole provided in the heel attaching section with an aperture 50 extending therethrough, a cap secured within said aperture and fashioned with an interior concave seat, a heel appressed against said section and formed in the upper section thereof with an upwardly extending socket and a horizontally extending slot intersecting said socket and effecting communication with the exterior of said heel, 55

a spring pressed nut positioned in said slot and capable of insertion in and removable from said slot while said heel is appressed against said sole, and a bolt fashioned with a hemispherical head seated in said seat of said cap for effecting swivel connection therewith and a shank extending through said nut whereby to secure said heel to said sole.

3. In a shoe, the combination of a sole provided in the heel attaching section with an aperture extending therethrough, a cap secured within said aperture and fashioned with an interior concave seat, a heel appressed against said section and formed in the upper section thereof with an upwardly extending socket and a horizontally extending slot intersecting said socket and effecting communication with the exterior of said heel, a spring pressed nut positioned in said slot and capable of insertion in and removable from said slot while said heel is appressed against said sole, a bolt fashioned with a hemispherical head seated in said seat of said cap for effecting swivel connection therewith and a shank extend-

ing through said nut whereby to secure said heel to said sole, and an insole lining carried by said sole covering said cap whereby to conceal the latter and preclude foreign matter from entering said cap.

4. In a shoe, the combination of a sole provided in the heel attaching section with an aperture extending therethrough, a cap within said aperture, a heel appressed against said section and formed in the upper section thereof with an upwardly extending socket and a slot intersecting said socket and effecting communication with the exterior of said heel, a nut positioned in said slot and capable of being inserted in and removed therefrom when said heel is against said sole, a bolt swiveled to said cap and extending through said nut for fixing said heel to said sole, and an insole lining carried by said sole covering said cap whereby to conceal the latter and preclude foreign matter from entering said cap.

JULIUS FARINA.
